(57) **CLAIM**

The ornamental design for modular building, as shown and described.

DESCRIPTION

The patent or application file contains at least one drawing executed in color. Copies of this patent or patent application publication with color drawing(s) will be provided by the Office upon request and payment of the necessary fee.

Fig. 1.1 is a right side view of the modular design, showing my new sign;

Fig. 1.2 is a left side view thereof;

Fig. 1.3 is a front view thereof;

Fig. 1.4 is a rear view thereof;

Fig. 1.5 is a bottom view thereof;

Fig. 1.6 is a top view thereof;

Fig. 1.7 is a perspective view thereof.

The shape of the claimed module is cuboid, which is formed by the enclosure of walls and beams; for the two sides of the module, one side is provided with walls while the other side is not provided with walls; the two end faces are provided with a triangular bay window; the bottom of the module is provided with floors; the top of the module is open structure; the interior of the module is divided into multiple spaces by walls; reproduction 1.7 is a perspective view showing the interior of the claimed design.
